WIRE HEADING TOOL

William A. Vinson, Madera, Calif.

Application August 30, 1946, Serial No. 693,871

4 Claims. (Cl. 78—17)

1

My invention relates to a device for deforming the end of a cylindrical element to form a head or enlargement thereon and will be exemplified as a hand tool for forming an enlarged head on the end of a wire by upsetting the end.

In electrically connecting the end of a wire to another wire, terminal connector, etc., my co-pending application Serial No. 714,508, filed December 6, 1946, and now abandoned, shows the desirability of employing an end-headed wire with the head fitting into a suitable space of a connector or terminal. It is desirable that the head be formed on the wire by a simple, portable and easily actuated device and it is an important object of the invention to provide a device usable in this connection or in deforming the end of other cylindrical elements.

Another object is to clamp the wire or other cylindrical element by use of a self-locking clamping means facilitating insertion, clamping and removal of the wire or other element. In its preferred embodiment, the invention employs a toggle means in this connection, preferably a pair of toggle jaws, and another object of the invention is to employ novelly related toggle jaws and a novel support therefor capable of withstanding strong spreading forces to which the jaws are subjected.

Another object is to employ two toggle jaws which are moved simultaneously and through equal angles and to urge these resiliently toward clamping positions.

Still a further object is to provide a device capable of deforming or heading wires or other cylindrical elements of various size without complicated adjustment of the device or replacing of parts thereof.

Further objects and advantages of the invention will be apparent to those skilled in the art from the following description of an exemplary embodiment.

Referring to the drawing:

Fig. 1 is a side elevational view of a hand tool embodying the invention.

Fig. 2 is an end view of the upper portion thereof, taken in the directions of arrow 2 of Fig. 1.

Fig. 3 is a top view, partially broken away, of the hand tool.

Fig. 4 is a fragmentary sectional view taken along the line 4—4 of Fig. 3.

Fig. 5 is a view showing the tool with a cover plate removed, being taken along the line 5—5 of Fig. 3, and

Fig. 6 shows the type of head formed on a wire by the tool.

2

Referring particularly to Fig. 1, the tool is indicated generally by the numeral 10 and is shown as including a body 11 integral with or secured to a fixed handle 12. The body 11 provides an upwardly facing space 15, best shown in Fig. 4, having an open upper end and, in the illustrated embodiment, two open sides one opening toward the front and one opening toward the rear. The front side is closed by a front side plate 16 held in place by a countersunk screw 17 and by a projecting screw 18 threaded into the body 11. The rear side is closed by a rear side plate 19 similarly held in place by screws similar to 17 or, if desired, formed integral with the body 11.

15 The invention includes a self-locking clamping means 20 for clamping a wire or other cylindrical element with its end extending in the space 15. This means is illustrated as a toggle means, preferably a toggle-acting vise means including 20 toggle jaws 21 and 22 pivoted to swing from a closed or clamping position, shown by full lines in Fig. 4, to an open or retracted position, the maximum open position being indicated by dotted lines 23 of Fig. 4.

25 The jaws 21 and 22 respectively provide forward ends 24 and 25 adjacent each other and rear ends 26 and 27.

A strong pivot means or hinge means is required to withstand the toggle forces involved in 30 the clamping operation and subsequent deforming operation. In this connection, I prefer to form each jaw with front and rear trunnions 28 and 29 respectively pivoting in one of two openings 30 in the front plate 16 and in one of two 35 openings 31 in the rear plate 19. In addition, the rear ends 26 and 27 of the jaws provide convex surfaces turning in surface contact with correspondingly shaped walls of arcuate channels 33 and 34 formed in the body 11 and facing each 40 other to open on, and in part determine the boundaries of, the space 15. The upper portion of the body provides relatively massive hook-like lips 35 and 36 forming these arcuate channels 33 and 34, the channels extending transversely of the 45 space 15 from one side of the body 11 to the other. Outward forces, arising from the toggle action of the jaws 21 and 22, can thus be transmitted directly to the body 11 through extensive-area bearing surfaces.

50 The jaws 21 and 22 thus form a trap-door-like structure for the upper end of the space 15. The formed ends 24 and 25 of these jaws are downwardly displaceable and provide for the clamping of ends of wires or other elements of 55 various sizes. In this connection, each forward

end provides an end surface 48 disposed angularly with respect to the midplane of the jaw, the two end surfaces being substantially parallel or actually in contact, if no wire is inserted, when the jaws are in closed position.

Gripping surfaces are formed on the forward ends of the jaws 21 and 22. Preferably, each end surface 48 carries a plurality of substantially semicircular cavities 49 of progressively different size, the cavities of one jaw being opposite correspondingly sized cavities of the other jaw and cooperating therewith in defining a plurality of element-clamping spaces 50 of different size. If desired, the inner walls of the cavities 49 may be roughened to give a firmer grip on the wire or other element but smooth walls are entirely satisfactory with the large toggle-applied clamping forces involved.

If the end of the wire or other element is to be flared, the lower end of each element-clamping space 50 may be enlarged to form a correspondingly shaped cavity 53. This cavity is formed half by one jaw and half by the other.

A suitable gear means is preferably provided so that the jaws 21 and 22 will swing together and so as to insure simultaneous and equi-angular movement thereof. The preferred gear means includes two gear segments 55 and 56 respectively connected to the forward faces of the jaws 21 and 22 as by dowels 57 extending from these jaws into correspondingly sized openings of the gear segments. These gear segments extend and move in indented spaces 58 in the forward face of the body 11 and each space provides a shoulder 59 which may be designed to be engaged by a corner 60 of the adjacent gear segment to limit the movement of it and its jaw toward closed position. The gear segments carry teeth 61 meshing with each other and formed on pitch circles concentric with the axis of the trunnions 28, 29. Movement of one jaw thus insures equal movement of the other.

In addition, the jaws are preferably urged toward their closed or clamping position. This may be accomplished by forming a tab 63 on the gear segment 55 and extending outward through an opening 64 of the front plate 16. One end of a spring 65 extends beneath the tab 63, this spring extending around a shouldered portion of the projecting screw 18 and having its other end tensioned by a pin 66 of the front plate 16. In view of the geared connection between the jaws, spring tension need be applied to only one of the jaws to be effective on both.

While clamped between the jaws 21 and 22, the end of the wire or other element is deformed or headed by upward movement of a corresponding deforming member 70. A plurality of these members 70 of progressively increasing size slide in corresponding holes 71 of the body 11. Each deforming member includes a pressure-exerting end, here shown as a tapered punch 72, extending into the space 15 and axially aligned with its corresponding element-clamping space 50. Each deforming member 70 has a head 73 which may engage the bottom of the body 11 to limit its upward movement.

The heads 73 are simultaneously moved upward by engagement with a shoulder 74 of a pressure member 75. This pressure member is moved upward by suitable connection to an operating handle 76, being shown as being integral therewith. The operating handle 76 is bifurcated to provide arms 77 on opposite sides of the body 11 and pivoted thereto by a pin 78. A looped

spring 80 resiliently urges the handles 12 and 76 apart.

The tool is very easily assembled and disassembled. With one or both plates 16, 19 removed, the jaws 21 and 22 can be slid into place transversely of the body 11 with the convex surfaces of the jaws in the arcuate channels 33 and 34. The gear segments 55 and 56 can be in place at this time or later inserted. The side plate or plates are then secured in place and the spring 65 hooked behind the pin 66.

The operation of the device, when used for heading a wire, is as follows. The end of the wire is inserted in the correspondingly-sized element-clamping space 50 until its end face engages the tip of the tapered punch 72. This movement will spread the jaws 21 and 22 slightly, displacing each of them slightly toward open position against the action of the spring 65. Any pressure tending to withdraw the wire will be resisted by an increased clamping of the jaws against the wire, due to the toggle action. As the handles 12 and 76 are squeezed, all of the deforming members 70 are moved upward. That one of the deforming members below the end of the clamped wire will be forced against the wire to deform or upset it and form a head or enlargement thereon. The shape of this head will be determined by the shape of the cavity 53 and the punch 72. A typical shape is shown in Fig. 6 which shows a wire 82 providing a head 83 having an annular tapered surface 84, conforming to the taper of the cavity 53, and an indented conical surface 85, corresponding to the shape of the tapered punch 72.

During the deformation, the upward pressure exerted by the deforming members 70 will be resisted by the toggle action of the jaws, the clamping action increasing with the upward pressure, thus permitting large deforming forces without slippage of the wire. When the wire is to be removed, it is necessary merely to apply downward pressure to one of the jaws to swing it and the other jaw into open position whereupon the headed wire can be removed.

While the invention has been exemplified as upsetting the end of a wire it should be clear that it can deform the ends of other cylindrical elements and that the shape of the cavity 53 and punch 72 can be modified to produce the desired enlargement. It will be clear also that various changes and modifications can be made without departing from the spirit of the invention and within the scope of the appended claims.

I claim as my invention:

1. In a device for deforming the end of a cylindrical element, the combination of: a body providing a pair of hinge means; a toggle-acting vise means for receiving and retaining the end of said cylindrical element and comprising a pair of toggle jaws respectively pivoting about said hinge means and providing forward ends adjacent each other and movable from an open position in which said ends are spaced from each other and disposed beyond a line joining said hinge means to a clamping position in which said ends are beyond said line but closer to each other and to said line than when in said open position, said forward ends providing gripping surfaces to engage and grip the end of said cylindrical element when disposed therebetween; a deforming member including a pressure-exerting end; means for mounting said deforming member to move relative to said body and axially toward said end of said cylindrical element when gripped by said

toggle jaws; and means for moving said deforming member perpendicular to said line and in a direction extending from said open to said clamping position of said toggle jaws to press said pressure-exerting end against the end of said cylindrical element to tighten the grip of the jaws on said element, and to deform same.

2. A device as defined in claim 1, in which said body provides a space and in which said hinge means comprise arcuate channels facing said space, said toggle jaws providing rear ends comprising convex bearing surfaces respectively disposed in said arcuate channels.

3. In a device for deforming the end of a cylindrical element, the combination of: a body providing a space open at one end and open on at least one side, said body providing two arcuate channels facing said space and extending from side to side thereof; a side plate for closing said side of said space; two toggle jaws normally extending across the open end of said space and providing forward ends adjacent each other and rear ends comprising convex bearing surfaces respectively in said arcuate channels; means for pivoting said toggle jaws to said side plate to move with said convex bearing surfaces within said arcuate channels, said movement being from an open position in which said forward ends are spaced from each other within said space to a clamping position in which said forward ends are closer to each other and closer to a line joining said arcuate channels, said forward ends providing gripping surfaces to engage and grip the end of said cylindrical element when disposed therebetween; a deforming member including a pressure-exerting end; and means for moving said deforming member perpendicular to said line and in a direction extending from said open to said clamping position of said toggle jaws to force said pressure-exerting end against the end of said cylindrical element to tighten the grip of

the jaws on said element, and to deform same.

4. In a device for deforming an end of an elongated element, the combination of: a tool body providing an operating axis; clamping means comprising a pair of toggle jaws pivoted on said tool body for holding the elongated element with its axis substantially coinciding with said operating axis, said jaws being movable in the direction of said operating axis from an open position on one side of a line connecting the points of pivotal connection of said jaws to said body to a clamping position on the same side of, but closer to said line; a deforming member carried by said tool body and movable relative thereto along said operating axis into engagement with the elongated element when the latter is held by said clamping means; and means for moving said deforming member perpendicular to said line and in a direction extending from said open to said clamping position of said toggle jaws into engagement with said end of the elongated element to tighten the grip of the jaws on said element, and to deform said end.
